UNITED STATES PATENT OFFICE.

AUGUSTUS J. THOMPSON, OF MALDEN, MASSACHUSETTS.

BUSTLE.

Specification of Letters Patent No. 25,854, dated October 18, 1859.

To all whom it may concern:

Be it known that I, AUGUSTUS J. THOMPSON, of Malden, in the county of Middlesex and State of Massachusetts, have invented a new and useful Improvement on the Spring-Bustle; and I do hereby declare that the following, taken in connection with the drawing which accompanies and forms a part of this specification, is a description thereof so full and exact as to enable those skilled in the art to practice my invention.

The nature of my improvement on the spring bustle consists in a certain arrangement and combination, substantially as hereinafter specified, of thin flat springs united at their ends to form the perimeter or outline of the bustle and spiral springs of conical configuration for joint action essentially as hereinafter set forth, and whereby a more easy lateral action of the whole bustle, for a given strength of outward thrust and steady vertical support, is secured to the bustle, to conform to swing in the gait of the wearer, and to meet various side thrusts or strains; and whereby other advantages are obtained for it over or as compared with other metallic spring bustle arrangements.

In the drawing (a) is the waist strap or belt, (b) the flat spring which encompasses the helical springs (c) and forms the outline of the bustle which by the action of the springs (c) is made of elliptical form. To form a broad bearing surface upon the body and for the base of the springs (c) I make a portion of the outline of the bustle of two flat springs as shown in the drawing.

The spring portions of the bustle are covered and are united together in the manner well known in the manufacture of "hoop skirts."

Provision is made in the clasps at (d) for uniting the bustle to one of the hoops (e) of a skirt to be worn in conjunction with it and the tapes shown at (f) may be tied around one or more of the hoops of a skirt extended forward to bring the fullness of the skirt more to the rear. The strap (g) fixed to the outer part of the bustle near the clasps (d) is designed to transfer the strain to the waist belt.

Such combination and arrangement of the within described springs possesses both

novelty and utility. Thus, there is a unity between the flat springs (b, b) made double or separated and spread where they constitute a base—that is, on their sides next to the body,—and the tapering spiral springs (c) having their base where the flat springs form a base and their smaller ends where the flat springs meet or form a narrower line or band on the outside. By such construction and arrangement of the springs, a steady central action is given to outward and inward thrust, and a stable vertical support to sustain the weight of the dress secured, while all sensation of localized pressure is removed and the whole bustle permitted to play laterally with greater freedom or ease to conform to swing in the gait of the wearer and to meet various lateral pressures, and which a mere flexible construction of the sides of the bustle less perfectly effects. By the spiral springs being of a single taper or conical form, all noise too or grating of their spirals is avoided during compression, and each of said springs may be so far compressed as to constitute a flat scroll and thereby made to occupy less space either than spiral springs of cylindrical figure or similar ones of hour glass form. But it is in the steady centralizing action of such spiral springs arranged as described, combined with the facility with which the same may be turned aside or bent over in the lateral play of the whole bustle, and the action in concert of the flat springs spread or divided at their base on the inside and serving to prevent objectionable vertical dip of the spiral springs, that the peculiar character of my improvement is made apparent; and, for a given weight and strength or efficiency, this my arrangement and combination of certain springs possesses greater self adaptability or freedom and general convenience and ease in use than most or all of those bustles in which inner and outer bands are connected by hoop and other springs that either too sensibly restrain side play or are too sensitive and local in that respect.

What is claimed therefore here is:

The combination, in a spring bustle, of a flat spring or springs (b) united at their ends to form the perimeter of the bustle or its

framework and spread or divided to establish a base at their bearing surface or surfaces against the body of the wearer, and spiral springs (c) of conical configuration and arranged to form cross ties to the flat springs, with their bases resting against the base formed by the latter and for action in con-

cert with the latter, and unitedly, essentially as herein set forth.

AUGUSTUS J. THOMPSON.
